UNITED STATES PATENT OFFICE.

FREADRICK P. DANUNHAUER, OF PHILADELPHIA, PENNSYLVANIA, AS-SIGNOR TO HIMSELF AND WILLIAM WOLF, OF SAME PLACE.

APPARATUS FOR DYEING YARNS.

SPECIFICATION forming part of Letters Patent No. 231,014, dated August 10, 1880.

Application filed May 25, 1880. (Model.)

To all whom it may concern:

Be it known that I, FREADRICK P. DANUNHAUER, of Philadelphia, in the county of Philadelphia and State of Pennsylvania, have invented a new and useful Improvement in Apparatus for Dyeing Yarns, of which the following is a specification.

In apparatus for dyeing yarns, as heretofore constructed, the skeins or hanks of yarn have been suspended from rollers or cross-bars placed above the tank containing the dyeing material, and the skeins have to be turned by hand to immerse all portions of the yarn. This operation is laborious, and requires handling of the skeins while saturated with the hot dye-stuffs.

The object of my invention is to turn the skeins of yarn regularly and automatically by machinery to the extent required; and my invention consists, first, in a series of nipping-rollers hung on vibrating arms and fitted for movement to and from the supporting-bars of the yarn to draw the yarn around the bars a regulated distance at each vibration; second, in an automatic stop-motion for shifting the driving-belt and stopping the mechanism when the desired number of turns have been given to the skeins, so that they may be removed.

The construction and operation will be described more particularly hereinafter with reference to the accompanying drawings, where-

in—

Figure 1 is a side elevation, partially in section, of a dyeing-tank fitted with my improvements, and Fig. 2 is a sectional plan view of the same.

Similar letters of reference indicate corresponding parts.

A is a tank of usual character for containing the dyeing liquid, and fitted at the top with the cross-bars *a* for supporting the skeins of yarn. These bars *a* are supported in open boxes at the upper ends of screws *b*, that are tapped into the sides of tank A, so that the bars may be adjusted vertically, and may also be lifted from their supports in applying and removing the skeins.

At one end of tank A, in suitable bearings, is fitted a cross-shaft, *c*, carrying fast and loose pulleys *d* *d'* for a driving-belt, and carrying at its ends the eccentrics *e* *e'*.

Upon each side of tank A, in boxes *f*', are fitted slide-rods *f*', one at each side of the tank, upon which rods arms *g* are fixed adjustably, and from the arms *g* rods *h* extend to 55 and are connected to cross-heads *g'*, that are fixed to the straps of eccentrics *e*. Upon the rods *f*' there are fixed curved standards *i*, that are formed at their upper ends to receive the shafts of rollers *k*, so that said rollers extend 60 across the top of the vat from the standard *i* at one side to the standards at the other side. Upon the standards *i* angle-levers *l* are pivoted, the upper ends of which extend horizontally, or nearly so, beneath the rollers *k*, and 65 are formed with open boxes for receiving the shafts of the rollers *m*, that also extend across and above the vat.

Upon each side of tank A is hung a cogged segment, *n*, the supporting-arms of which are 70 slotted to receive the adjustable crank-pins of rod *n'*, that pass to and are connected with the cross-heads *g'*. Above and meshing with the segments *n* are racks *o* *o*, that are suspended from links *o'*, that connect the lower ends of 75 the angle-levers *l*. These racks *o* are hung to links *o'* by a knuckle-jointed connection at one end, so that the outer ends of the racks are free to accommodate themselves to the curved movement of the levers *l*, and springs *m'* between the racks and links serve to retain the rack in gear during such movement.

k *k'* are slotted guides attached to the sides of the tank to prevent side movement of the segments *n*, and forked pieces *l'*, attached to 85 the racks *o* and extending at opposite sides of links *o'*, prevent lateral movement of the racks. By this construction the revolution of the shaft *c* imparts a reciprocating movement to the rods *f* and oscillates the segments *n*, which 90 movement of the segments, acting through racks *o*, gives a vibratory movement to the angle-levers *l* at the same time they reciprocate with the standards *i*.

There is a pair of the rollers *k* *m* for each 95 bar *a*, and the devices described being properly adjusted, said rollers *k* *m* first move toward their respective bars *a*. The rollers *m* then close up against rollers *k*, withdraw, and are opened during their backward movement. 100 By adjustment of arms *g'* on rods *f* and the connection of rods *n'* to the segments *n* the

time of the opening movement may be varied and the pull on the skeins at each reciprocation regulated. The skeins are to be suspended, as shown, both by the bars *a* and rollers *m*, so that when the rollers close together they grasp the skeins, and at the backward movement draw them over the bars, thus turning the skeins and bringing all parts into the liquid.

To automatically arrest the movement when the skeins have been turned a definite number of times, I use the automatically-acting mechanism next described for shifting the belt from the fast pulley *d* to the loose pulley *d'*.

Upon a stud at one side of tank *A* is hung a ratchet-wheel, *p*, and also a pawl, *p'*, engaging with wheel *p* to prevent back movement. The wheel *p* is provided on its outer face with a number of apertures, arranged in a circle, to receive a screw-pin, *q*.

Upon tank *A*, adjacent to shaft *c*, is hung a lever, *r*, the upper end of which projects in the path of a cam, *r'*, on shaft *c*. To the lower end of lever *r* is hung a rod, *s*, that extends through suitable guides at the side of the tank, and carries at its outer end a spring finger or pawl, *s'*, that engages with ratchet-wheel *p*. The cam *r'* acts at every revolution of shaft *c* to move lever *r* and draw-rod *s* to turn the ratchet-wheel, and a coiled spring, *q'*, on rod *s* throws the rod back after the cam has acted.

At the end of tank *A* is fitted a slide-rod, *t*, carrying the belt-shifting arms *t'*, and also carrying a coiled spring, *u*, that tends to move the rod *t* and shift the belt to the loose pulley. The rod *t* projects at the side of the tank against a plate on the end of a rod, *v*, that is fitted in suitable guides, so that the rod *t* is held from being moved by the spring *u*, and the belt thereby retained on the fast pulley. The other end of rod *v* extends in front of the ratchet-wheel *p*, and has its end bent down in the path of the pin *q*. The coiled spring *v'* on rod *v* retains said rod in the position just described.

The ratchet-wheel being turned a short distance at each revolution of shaft *c*, the pin *q*

is thereby brought sooner or later, according as it is placed, in contact with the bent end of rod *v*, and draws the said rod endwise, thereby releasing the belt-shifter *t* and allowing the spring *u* to force the belt to the loose pulley.

By lifting the bars *a* and rollers *m* the skeins may be removed and others put in their place. The belt is then to be moved back to the fast pulley by the hand-lever *w*, that is connected with rod *t*, and the latter is held by rods *v*, as before.

By the use of this apparatus hand-labor is dispensed with for turning the skeins in the dyeing-liquid, the yarn is turned regularly and uniformly and to the extent required.

Having thus fully described my invention, I claim as new and desire to secure by Letters Patent—

1. In apparatus for dyeing yarn, the combination, with the tank or vat and supporting bars of the skeins, of the pairs of rollers *k m* and operating mechanism, substantially as and for the purpose set forth.

2. In apparatus for dyeing yarn, the reciprocating rods *f*, standards *i*, rollers *k*, vibrating levers *l*, and rollers *m*, combined together and with the tank *A* and fixed bars *a*, substantially as and for the purposes set forth.

3. The racking-segments *n*, racks *o*, and links *o'*, combined with tank *A*, the bars *a*, and the bent levers *l*, hung on the reciprocating standards *i*, and the rollers *k m*, carried by standards *i* and levers *l*, for operation as shown and described.

4. In apparatus for dyeing yarns, in combination with the tank *A* and the reciprocating feed-rollers *k m*, operated by connections from the driving-shaft *c*, the ratchet-wheel *p*, the rod *v*, fitted for movement by wheel *p*, the sliding belt-shift *t*, the lever *r*, and the reciprocating rod *s*, carrying pawl *s'*, engaging the ratchet-wheel, substantially as and for the purposes set forth.

FREADRICK P. DANUNHAUER.
